SHARPENING OR HONING APPARATUS FOR
RAZOR BLADESGuillaume Barsch, Lucerne, Switzerland, assignor
to the firm of Industrie A.-G. Allegro, Emmen-
brucke-Lucerne, SwitzerlandApplication August 7, 1933, Serial No. 684,069
In Germany August 11, 1932

10 Claims. (Cl. 51—58)

The present invention relates to a sharpening or honing apparatus for two-edged razor blades, in which the blades are arranged on a rocking blade-holder and are operated upon on both sides by sharpening members provided on rocking levers. The invention has for its object to provide a sharpening device which, while being simple and cheap to manufacture, of comparatively small size and simple to manipulate, 5 enables a particularly rapid and satisfactory sharpening or honing of the razor blades to be obtained.

According to the present invention the blade holder stands under the influence of a spring 15 pressing against a lateral lug or extension on the blade holder which spring after movement of the blade holder from one alternative angular position to another has been initiated suddenly tilts the blade-holder to complete such movement and resiliently maintains the holder and blade in its alternative positions so as to afford a resilient engagement between the blade and said sharpening members.

The invention is more particularly described 25 with reference to the accompanying drawings, in which:

Figure 1 is a view of the interior of the sharpening apparatus after the removal of the casing cover. The opening provided in this latter for inserting and removing the blades, and the guide-slot for the handle serving for the movement of the rocking levers, are, however, indicated in broken lines. The rocking levers are shown shortly before reaching their left hand 35 end position.

Figure 2 is a side elevation of the rocking blade-holder alone.

Figure 3 shows a link adapted for connecting the rocking levers and fitted with a handle, the 40 rocking levers being omitted.

Figure 4 is a view of the inside of a sharpening device similar to Figure 1, in which the hones or whet-stones are spring-mounted on the rocking lever.

Figure 5 is a plan view of one of the two rocking levers, after the removal of the spring-mounted hone.

Figure 6 is a longitudinal section through the rocking lever on the line C—D of Figure 5.

Figure 7 is an end elevation of a rocking lever with a hone or whet-stone in position.

Figures 8 and 9 show the blade-holder in cross-section on the line A—B of Figure 4 in the two turning positions.

The sharpening and honing apparatus is ar-

ranged in a casing 1, preferably of metal, having a removable cover 16. The sharpening members 2, which preferably consist of hones or whet-stones, are arranged on the inner side of two oscillating or rocking levers 4, movable to and fro on both sides of the blade 3. The oscillating or rocking levers 4 are connected by a link 5, the handle 6 of which is movable in a guide-slot 7 in the cover 16, indicated in dotted lines in Figs. 1 and 4. The fulcrum of the oscillating or rocking levers, formed by pins 8 on the casing bottom 1, are arranged in such a way, that the sharpening members 2 have oscillatory movement in paths disposed obliquely to the edges 9 of the blade 3 on the mutual rocking of 15 the levers 4 by to-and-fro movement of the handle 6 while their sharpening paths intersect each other and the edges 9 of the blade 3, rocked on each stroke of the levers 4, are operated upon on both sides by the sharpening 20 members 2, and in fact in opposite directions to each other.

The rocking blade-holder 10 according to the invention is pivoted at its ends in opposite walls of the casing and is under the influence of a spring 17, which resiliently presses the blade 3 on the hones 2 during the sharpening. The spring 17 completes the movement of the blade-holder 10 from one of its positions to the other after its turning movement has been initiated. To initiate 30 the turning movement of the blade-holder 10 after each stroke of the rocking levers 4, the blade holder 10, which as shown in Figure 1 is accessible through an opening 11 in the casing cover 16 for securing the blade 3, has tongues 12 and 13, 35 bent if desired out of the sheet metal of the holder 10, and directed at the ends in different directions, namely obliquely upwards and obliquely downwards which alternatively initiate the rocking movement of the holder 10 and thus of the 40 clamped blade 3 through engagement by the rocking levers 4 or by projections or cams 14 and 15, provided on the rocking levers. After passing its mid angular position, a sudden tilting of the blade-holder 10 is effected into the respective 45 angular positions by the action of the spring 17. The spring 17 bears at one end against a lug 29 of the blade-holder 10 having a cross-bar 19, and at its other end against an abutment 18 on the casing 1, and in the examples of construction 50 illustrated is carried by a push-rod 30, which at one end is connected with the cross-bar or pivot 19 on the lug 29 in the manner of a knee-joint, while the other end projects freely through the abutment 18. The spring 17, which effects the sudden 55

tilting of the blade-holder into the respective angular positions after passing the middle position, has the further function of holding the blade-holder resiliently in the two turning positions, 5 that is to say, to press resiliently the edges 9 of the blade on the hones 2 during the sharpening of the blade 3.

The tongues 12 and 13 of the blade-holder 10 are of such length in the example shown in Figures 1 and 2, that they limit the rocking movement of the blade-holder 10 and the blade 3 by 10 striking against the bottom 1 and the cover 16 of the casing. Instead of using the tongues 12 and 13 as stops for limiting the movement of the 15 blade-holder 10, projections 31, 32 directed to opposite sides may also be provided as shown in Figures 8 and 9, on the push-rod 30 serving for the mounting of the spring 17, at the knee-joint 19 or in its proximity. These projections limit 20 the rocking movement of the blade-holder 10 by coming in contact with the bottom 1 and cover 16 of the casing.

The tongues 12 and 13 on the blade-holder 10 and the projections or cams 14 and 15 of the 25 rocking levers 4 cooperating with them are associated with one another in such a way that the edges 9 of the blade 3 are honed in an outward direction that is to say, away from the edges of the blade. By shifting the projections or cams 14 and 15 to the opposite side of the levers 4, and 30 by a suitably different bending of the tongues 12 and 13 of the blade-holder, the result can be obtained that the edges 9 of the blade are sharpened from outwards to inwards or towards the edges 35 of the blade.

In addition to the resilient mounting of the 40 blade-holder 10 in the two turning positions under the action of the spring 17 the hones are as shown in Figures 4 to 7 also spring-mounted in the rocking levers, whereby the advantage is obtained that in all cases the hones 2 apply themselves gently 45 to the edges 9, even with somewhat curved blades, and produce a satisfactory sharpening. Further, injury and cutting of the hones or whetstones 2 as well as damage to the blade edges 9, more particularly on engagement of the hones on 50 the corners of the blades are avoided. The spring-mounting of the hones 2 on the rocking levers is so performed that the hones are resilient so that they can be depressed as a whole as well as at either of both ends alone. The springs 55 38 which influence the hones 2 act on separate holders 33, which are mounted on the rocking levers 4. The springs 38 are preferably arranged between the holder 33 and the rocking lever, and in the construction shown are formed by stamped-out and bent tongues which are formed from the material of the holders 33 themselves, 60 for instance sheet steel. The holders 33 embrace the hones 2 on the two ends thereof with bent up tongues 34 and 35, and are secured against longitudinal displacement by stops on the levers. The securing against longitudinal displacement 65 is effected in one direction by two stop tongues 36 on the rocking lever 4 laterally embracing the hones 2 and bearing on the tongues 35 of the holder 33, and in the other direction by the bearing of the sheet metal holder with the free end of one spring 38 against stop 37 provided 70 on the bottom of the rocking lever 4. The tongues 36 and 15 of the rocking lever 4 laterally embracing the hone at the same time limit the lift of the springs 38 and thus of the hones 2.

The tongues 34 of the holders 33 are preferably 75 bent at an obtuse angle, and are only of such a

height that the hone, which is preferably roof-shaped or V-shaped in profile, can be easily changed when required. For this purpose, it is simply necessary to depress the hone 2 at the inner end and then push it outwards and it then 5 slides over the obtusely bent tongue 34 of the holder 33 and thus can be withdrawn from this latter and from the rocking lever 4.

The strength of the springs 38 is preferably 10 less than that of the spring 17 which tips the blade-holder 10 in the turning positions and presses the blade 3 on the hones 2, whereby a particularly uniform and satisfactory honing off of the blade 3 is ensured.

To fasten the blades 3 in position on the blade-holder studs 20 and 21, hooks or the like are 15 provided on the blade-holder 10, one of which studs 20 is arranged on a holder 23 that is displaceable in an axial direction against the action of a spring 22 (Figure 2). The axially displaceable part 23 20 of the blade-holder 10 forms its one bearing pin and projects with the end 24 beyond the side 25 wall of the casing, (Figs. 1 and 4), so that the adjustment of the stud 20 necessary for the insertion and removal of the blade 3 can be obtained in a particularly simple way from the outside 30 of the casing by pressing on the end 24, which is formed as a knob of the displaceable holder 23.

The rocking levers 4 and their link 5 may 35 also be spring-mounted as well as the blade-holder 10 and the hones 2. According to Figure 3, the pivots provided between the rocking levers 4 and the link 5 are under the action of springs 25, which press the rocking levers 4 and the link 5 provided with slide-shoes 26 against the bottom 35 1 and the cover 16 of the casing. The springs 25 are fitted in bearing bushes 27 of the link 5 which are inserted on the pins 28 of the rocking levers 4, which are not shown in Fig. 3.

I claim:

1. A sharpening or honing apparatus for two 40 edged razor blades comprising a pair of oscillatory honing tools, said tools oscillating in planes substantially parallel to, and in the direction of, the length of the axis of the holder, a rockable 45 blade holder located between said honing tools and having tongues sloping in opposite directions therefrom for periodic engagement by said honing tools to initiate angular displacement of the blade holder from one alternative position to the other to present alternate edge surfaces on opposite 50 faces of the blade held in said holder to the action of said honing tools, said honing tools being adapted to engage alternately and simultaneously on opposite sides of said blade, and resilient means for completing said angular displacement of said blade holder from one alternative position to the other and for resiliently maintaining the blade holder in either of its alternative angular positions with the opposite faces of 60 the edges of the blade respectively operatively presented to the respective honing tools.

2. A sharpening or honing apparatus for two-edged razor blades comprising a rockable blade 65 holder having tongues sloping in different directions therefrom, a pair of oscillatory honing tools adapted to engage simultaneously on opposite sides and alternately the respective edge surfaces of a blade held in said holder, means associated with said tools for periodically initiating movement of the blade holder from one angular position to the other during the operation of the tools to present alternate edge surfaces on opposite faces of said blade to the action of said tools and means for completing such movement and for 75

resiliently maintaining the blade holder in either of its alternative angular operative positions.

3. A sharpening or honing apparatus for two-edged razor blades comprising a casing having 5 side walls, base and cover, spaced pivots on said base, a pair of rockable levers mounted on said pivots, a rockable blade holder pivotally supported by opposite walls of said casing and having tongues sloping in different directions there- 10 from for respective engagement by said levers and adapted for abutment respectively with the base or cover of the casing to locate the holder in its alternative angular positions, sharpening members on said levers adapted to engage on a 15 blade secured to said holder, a lug extending from the blade holder, a push rod slidably supported at one end by the casing, and pivotally connected at its other end to said lug and a compression spring on said push rod adapted to complete the 20 angular displacement of the lug and blade holder from one alternative angular position to the other after initiation of such angular movement by engagement of a lever with one of said tongues.

4. A sharpening or honing apparatus for two-edged razor blades comprising a casing having side walls, base and cover, spaced pivots on said base, a pair of rockable levers mounted on said pivots, a rockable blade holder pivotally supported by opposite walls of said casing and located 30 between said levers and having tongues sloping in different directions therefrom for respective engagement by said levers to initiate angular displacement of the blade holder from one alternative angular position to another, sharpening 35 members on said levers adapted to engage on a blade secured to said holder, a lug extending from the blade holder, a push rod slidably supported at one end by the casing and pivotally connected at its other end to said lug and a compression 40 spring on said push rod abutting at one end against the casing and adapted to complete the angular displacement of the lug and blade holder from one alternative angular position to the other after initiation of such angular movement 45 by engagement of a lever with one of said tongues, said push rod having a transverse abutment at its end adjacent the lug for engagement with one end of said spring, the opposite ends of said abutment being adapted for engagement re- 50 spectively with the cover and base of the casing for locating the blade holder in its alternative angular positions.

5. A sharpening or honing apparatus for two-edged razor blades comprising a casing having 55 side walls, base and cover, spaced pivots on said base, a pair of rockable levers mounted on said pivots, a rockable blade holder pivotally supported by opposite walls of said casing and having tongues sloping in different directions therefrom 60 for respective engagement by said levers to initiate angular displacement of the holder from one alternative angular position to another, sharpening members on said levers adapted to engage on opposite sides of a blade secured to said holder, a spring located between the holder and the casing adapted to complete the angular displacement of the blade holder and resiliently to maintain the holder in its respective positions to afford 65 resilient engagement between the blade and the sharpening members, holders for said sharpening members mounted on said levers and having resilient tongues extending therefrom and bearing against said levers towards both ends of the sharpening members for resiliently suspending the said members especially in their longitudinal 70

middle line to regulate the pressure of the sharpening members and to ensure their adaptiveness to any position of the razor blade.

6. In a sharpening or honing apparatus for two-edged razor blades as claimed in claim 5, 5 bent tongues extending from each lever for transverse engagement around the hone to limit outward displacement of the hone away from the lever and relatively shallow end lugs on each of the hone holders bent at an obtuse angle to the 10 base of the holder to enable the hone to be withdrawn from the outer end of the lever and holder by depressing and pushing outwardly the inner end of the hone.

7. A sharpening or honing apparatus for two-edged razor blades comprising a casing having side walls, base and cover, spaced pivots on said base, a pair of rockable levers mounted on said pivots, a pin on each of said levers, a connecting link between said levers, a socket at each end of 15 said link for engagement on said pins, a spring in each of said sockets, a manual operating member on said connecting link, shoes on said link for sliding engagement with base and cover of the casing, a rockable blade holder pivotally supported by opposite walls of said casing and located between said levers and having tongues sloping in different directions therefrom for respective engagement by said levers to initiate angular displacement of the holder from one 20 alternative angular position to another, sharpening members on said levers adapted to engage on opposite sides of a blade secured to said holder and a spring located between the holder and the casing adapted to complete the angular dis- 25 placement of the blade holder.

8. A honing apparatus for two-edged razor blades comprising a casing having side walls, a base and cover spaced pivots on said base, a pair of oscillatory honing tools respectively pivotally 40 mounted on said pivots, a rockable blade holder pivotally supported by and between said side walls and having tongues extending in different directions for respective engagement by said tools to initiate angular displacement of said holder 45 from one alternative angular position to the other, and resilient means for completing such alternative rocking movements to such operative angular positions wherein alternate surface edges of the blade are presented to the action of the 50 honing tools.

9. A honing apparatus for two-edged razor blades comprising a support, a pair of oscillatory honing tools pivotally mounted on said support, a blade holder disposed between said tools and 55 rockably mounted in said support and adapted to hold a razor blade with one edge surface in contact with one of said honing tools and the opposite edge surface of the other edge simultaneously in contact with the other of said honing tools, 60 tongues respectively extending in opposite directions from the respective end portions of said holder, one of said tongues being engaged by one of said tools as the latter approaches the final stage of its movement in one direction to 65 initiate a rocking movement of the holder in one direction and the other of said tongues being engaged by the other of said tools as the latter approaches the final stage of its movement in the reverse direction to initiate a reverse rocking 70 movement of the holder, and resilient means for completing such alternate rocking movements of said holder and for yieldingly and simultaneously pressing the respective edge surfaces of the blade held in said holder in opposite directions against 75

the opposed faces of the oppositely moving oscillatory honing tools while the latter are in contact with said surfaces.

10. A honing apparatus for two-edged razor blades comprising a support, a pair of oscillatory honing tools pivotally mounted on said support, a blade holder disposed between said tools and rockably mounted in said support and adapted to hold a razor blade with one edge surface in contact with one of said honing tools and the opposite surface of the other edge simultaneously in contact with the other of said honing tools, the free end portions of said tools and the end portions of said holder being so formed and related that as one of said tools approaches the final stage of its movement in one direction its free end portion

will strike the cooperating end portion of the holder to initiate a rocking movement of the holder in one direction and as the other of said tools in turn approaches the final stage of its movement in the reverse direction its free end portion will strike the other and cooperating end portion of the holder to initiate a reverse rocking movement of the holder, and resilient means for completing such alternate rocking movement of said holder and for yieldingly and simultaneously 10 pressing the respective edge surfaces of the blade held in said holder in opposite directions against the opposed faces of the oppositely moving oscillatory honing tools while the latter are in contact with said surfaces. 15

GUILLAUME BARSCH.
